United States Patent

Des. 237,449
Patented Nov. 4, 1975

237,449

PASTRY SERVER OR THE LIKE

Edward N. Montesi, Barrington, R.I., assignor to Dart Industries Inc., Los Angeles, Calif.

Filed Aug. 5, 1974, Ser. No. 494,950

Term of patent 14 years

Int. Cl. D7—03

U.S. Cl. D7—142

FIG. 1 is a top plan view of a pastry server or the like showing my new design;

FIG. 2 is a side elevational view thereof;

FIG. 3 is a bottom plan view thereof;

FIG. 4 is a front elevational view thereof; and

FIG. 5 is a rear elevational view thereof.

I claim:

The ornamental design for a pastry server or the like, substantially as shown.
